HOSIERY INSPECTION AND SEAMING CONSOLE

Ralph B. Jones, Greensboro, N.C., assignor to Textile Metals & Plastics, Inc., Greensboro, N.C., a corporation of North Carolina

Filed June 24, 1966, Ser. No. 2,801

Term of patent 14 years

(Cl. D55—1)

FIG. 1

FIG. 2

FIG. 3

FIGURE 1 is a perspective view looking at the front and one end of the hosiery inspection and seaming console;

FIGURE 2 is a plan view of the hosiery inspection and seaming console; and

FIGURE 3 is an end view looking at the left hand end of FIGURE 2.

The back of the console is plain and unornamented. The yarn carriers and sewing machine shown in dotted lines in FIGURES 1 and 2 are shown for purposes of illustration only and do not form any part of the invention.

The two tubular elements at the left of FIG. 2 are of indeterminate length and are fragmentarily shown for convenience of illustration.

I claim:

The ornamental design for a hosiery inspection and seaming console, substantially as shown and described.
